(57) **CLAIM**

The ornamental design for a vacuum cleaner, as shown and described.

DESCRIPTION

FIG. 1 is a top, front, and right side perspective view of the smaller tank shown in FIG. 2.

FIG. 2 is an exploded perspective view.

FIG. 3 is a perspective view of the vacuum cleaner in assembled condition.

FIG. 4 is a top plan view of the vacuum cleaner as seen in FIG. 3.

FIG. 5 is a left side elevation of the vacuum cleaner as seen in FIG. 3; and,

FIG. 6 is a front elevation of the vacuum cleaner as seen in FIG. 3.

FIG. 1 is shown separately for clarity of illustration. The claimed design is for a full vacuum cleaner in assembled condition as seen in FIG. 3.
